UNITED STATES PATENT OFFICE.

CHARLES H. KUHNE, OF BUTLER, PENNSYLVANIA.

MOTOR.

SPECIFICATION forming part of Letters Patent No. 295,179, dated March 18, 1884.

Application filed August 4, 1883. (No model.)

To all whom it may concern:

Be it known that I, CHARLES H. KUHNE, of Butler, in the county of Butler and State of Pennsylvania, have invented certain new and useful Improvements in Motors; and I do hereby declare the following to be a full, clear, and exact description of the invention, such as will enable others skilled in the art to which it appertains to make and use the same.

My invention relates to an improvement in motors, the object being to provide a motor, to be actuated by steam, or air, or fluids, that shall be simple in its construction and certain and uniform in its operation. A further object is to provide a motor wherein dead-centers will be avoided; and with these ends in view my invention consists in the parts and combinations of parts, as will be more fully described, and pointed out in the claims.

The accompanying drawing represents my invention partly in longitudinal section and partly in side elevation.

A represents the large cylinder, and B the small cylinder, of the motor. These cylinders are preferably cast in a single piece, but, if desired, may be cast separate and bolted together. The outer head, a' , of the cylinder B may be cast integral with the cylinder; or the head may be detachable from the said cylinder, which is the preferred form of construction, as it gives the ready access to the interior of the cylinder for the purpose of renewing the piston-packing.

C is the piston-rod, and D E the pistons, secured thereto or cast integral therewith, the latter form of construction being preferred for the sake of cheapness. These pistons may be packed in any manner with either leather or metal packing. The piston-rod C extends through the stuffing-box C', attached to the head C' of cylinder A, and may be connected to the piston-rod of a pump, or to a pitman for actuating a crank-shaft, or in any other desired manner to transmit the power to machines to be driven. I would have it understood that I nowise limit myself to the employment of my improvement for any particular purpose.

The cylinder B is provided with a port, B', near its outer end, which connects with a steam-passage, b', formed in the cylinder in the process of casting, said passage b' leading to and connecting with the port B'. Cylinder A is

provided with a steam-passage, d, one end of which communicates with a port, d'. The inner end of cylinder A is also provided with a port, e, which connects with the port e'.

Within the inner end of cylinder B is located a ring, E', which is provided at one side with a recess, F, said recessed ring constituting a slide-valve, as will hereinafter appear. The adjacent faces of the two pistons have each secured thereto a ring or washer, G. These washers come in contact with the ring E' and shift it at the termination of each stroke of the pistons.

H is a pipe provided with a throttle-valve, I, for regulating the supply of steam, air, or fluid for regulating the motor. This pipe is provided with a T-coupling, J, from one arm of which extends a pipe, K, that leads to the outer end of the cylinder B. To the other arm of the coupling J is connected a pipe, j, which is attached to the bottom of the valve-casing L, the latter being connected by a pipe, L', to the outer end of cylinder A. Within the valve-casing L is located a differential piston consisting of the small piston m, which latter is always exposed to the action of the live steam, and large piston n, connected by the rod m'. This differential piston is upheld by the spiral spring O, which may be inserted and adjusted by means of the nut P.

The operation of the motor is, briefly, as follows: When the parts are in the position shown in the drawing, steam is admitted by opening the throttle, to the outer end of cylinder A, and through pipe K to the outer end of cylinder B. Owing to the fact that the area of the piston D in the cylinder A is considerable in excess of the area of piston E in cylinder B, the piston D in the large cylinder is driven toward its inner end until the washer G strikes the ring E', shifting it so that its recess F will connect the ports B' d' and allow the steam in the outer end of cylinder B to flow through the port B', steam-passage b', port B', and recess F, port d', steam-passage d, port d' into the upper end of valve-casing L, forcing the valve down until the lower and smaller piston, m, has descended below the steam-port d', thereby allowing steam in the outer end of cylinder A to exhaust freely through the port d' over the small piston m, and out through the exhaust-pipe m'. As soon as the steam is

allowed to exhaust from the outer end of cylinder A, the steam will operate on the small piston E and drive both pistons in the opposite direction until the completion of the 5 turn-stroke, when the washer on the small piston E shifts the valve E' to the position shown in the drawing, which allows the steam between the large piston and the upper end of the valve-easing to exhaust through the port 10 d^2 , passage d, port d' into the space F, passage e^2 , port e into the space between the two pistons, and outwardly through passage F', and enables the steam pressing against the outer 15 face of the small piston m to force the valve up in the position shown. The ring-valve E', shifted in the manner last described, allows the differential valve to rise, and opens the passage for the flow of steam into the outer end of cylinder A, when the pistons are forced 20 in the opposite direction, as hereinbefore described.

From the foregoing it will be observed that there are no dead-centers, and hence the motor can be started or stopped at any part of its 25 stroke. Again, the construction of the motor is exceedingly simple and cheap, and the parts are so arranged as to insure certainty in its operation.

It is evident that slight changes in the construction and relative arrangement of the several parts might be resorted to without departing from the spirit of my invention, and hence I would have it understood that I do not 30 confine myself to the exact construction shown 35 and described, but consider myself at liberty to make such changes and alterations as fairly fall within the spirit and scope of my invention.

Having fully described my invention, what I 40 claim as new, and desire to secure by Letters Patent, is—

1. The combination, with differential main pistons and a valve shifted by said pistons, of a differential valve for regulating the exhaust, 45 substantially as set forth.

2. The combination, with differential main pistons, a valve shifted by said pistons, and pipes for admitting steam to both pistons, of a differential valve for regulating the exhaust 50 and cutting off the supply of steam to the main piston, substantially as set forth.

3. The combination, with differential main pistons, a valve shifted by said pistons, and pipes for admitting steam to both pistons, of a differential valve connected with the pipe 55 which supplies steam to the larger piston, and adapted to regulate the exhaust and cut off the supply of steam to the large piston, substantially as set forth.

4. The combination, with differential main 60 pistons, a valve shifted by said pistons, and pipes for supplying steam to both pistons, of a differential valve connected with the pipe which supplies steam to the large or main piston and adapted to regulate the exhaust and 65 cut off the supply of steam in the large piston, and a throttle-valve situated beyond or outside of the two supply-pipes, substantially as set forth.

5. The combination, with differential cylinders 70 and pistons, a sliding valve, and rings or washers for moving the valve, of a differential valve for cutting off the supply of steam in the large piston and regulating the exhaust of both cylinders, substantially as set forth. 75

6. The combination, with differential cylinders and pistons, the latter being provided with suitable rings or washers, the sliding valve, the steam-supply pipe, exhaust-passage F', the ports B', B, d^2 , e^2 , e, d' , and d'' , and 80 steam-passages b^2 d' , of the differential valve provided with the exhaust pipe m^2 , and adapted to cut off the supply of steam in the main piston and regulate the exhaust of both cylinders, substantially as set forth. 85

7. The combination, with the pistons and cylinders, constructed as described, and the steam-supply pipes, of the differential valve connected with the cylinders, as described, and adapted to cut off the supply of steam in the 90 large or main piston and regulate the exhaust of both cylinders, substantially as set forth.

In testimony whereof I have signed this specification in the presence of two subscribing witnesses.

CHARLES H. KUHNE.
